UNITED STATES PATENT OFFICE.

HENRY W. PAINE, OF EAGLE GROVE, IOWA.

VALVE-SPRING-COMPRESSING TOOL.

1,401,920.

Specification of Letters Patent. Patented Dec. 27, 1921.

Application filed January 3, 1921. Serial No. 434,470.

To all whom it may concern:

Be it known that I, HENRY W. PAINE, a citizen of the United States, residing at Eagle Grove, in the county of Wright and 5 State of Iowa, have invented a new and useful Valve-Spring-Compressing Tool, of which the following is a specification.

This invention relates to implements for compressing the valve springs of internal 10 combustion engines.

The principal object of the invention is to provide a device enabling an operator to compress all the valve springs on the detachable head of valve-in-head motors so 15 that the valve keys may be removed, whereupon the valves themselves may be taken out for re-grinding.

A further object of the invention is to provide a tool which is well adapted for use in 20 compressing valve springs of other types of motors, such as those which employ valve cages.

The invention will be best understood from a consideration of the following detailed description taken in connection with the accompanying drawing forming part of this specification, with the understanding, however, that the invention is not confined to any strict conformity with the showing 25 in the drawing, but may be changed and modified so long as such changes and modifications mark no material departure from the salient features of the invention as expressed in the appended claims.

30 In the drawing:—

Figure 1 is a perspective view of the improved device.

Fig. 2 is a plan view of the same showing the spring in the act of being compressed.

40 Fig. 3 is an end elevation with parts in section showing the spring slightly compressed.

The device employs a support or table 5 providing a base of a size sufficient to receive thereon a detachable head 6 of a valve-in-head motor. This base has an abutment 5^a near one longitudinal edge against which the detachable head may be thrust. At the ends of the abutment 5^a are standards 7 45 which rigidly support a rod 8 parallel to the base 5.

A lever is connected to the rod 8 so that it may slide freely the length of said rod and may swing equally freely about the rod 55 as an axis. To permit this, the lever has an eye 9 at one extremity, the other end having

a handle 14. That portion of the lever adjacent the eye is straight as indicated at 10, and the portion 13 adjacent the handle is likewise straight and in alinement with the 60 portion 10. Intermediate the portions 10 and 13 the lever has an offset portion 12. This offset portion is preferably formed by giving a double bend to the lever whereby the offset portion of the lever is not arcuate 65 but on the contrary is straight for the greater part of its length. An arm 11 is formed integrally with the lever and is bent at an angle to the portion 10 and then in parallelism with the straight portion of the 70 offset 12. This arm does not have a length equal to the offset 12 but terminates at such a distance from the offset as well as from the portion 13 that a wide gap is left between the extremity of the arm and the portion 13. 75 Thus the lever may be said to be forked intermediate its ends.

When the detachable head is placed upon the base 5, the lever is slid along the rod 8 until it becomes opposite one of the valves. 80 Then it is depressed until the arm 11 and the straight part of the offset 12 is swung down into engagement with the valve cap 17. This depresses the spring 16 and allows the valve key 18 to be withdrawn. 85 Thereafter the valve itself may be taken out and re-ground. When the parts are to be re-assembled, the spring 16 will be placed about the valve stem 13, then the valve cap 17 will be laid upon the upper end of the 90 spring, whereupon the lever will be swung down to depress the spring so that the key 18 may be replaced.

The base is of sufficient size to receive all types of detachable heads and the provision 95 of the forked lever permits depression of the springs regardless of any variation in size of said heads. By the use of this device, the valves of motors having any number of cylinders are quickly removed with a minimum of trouble. When the valves are in 100 cages it is easy to support them upon the base 5 in such a way that the lever may compress their springs as well.

What is claimed is:—

1. The combination with a base and a rod mounted rigidly in parallelism with the base, of a lever slideable and swingable on said rod, said lever being forked whereby it may be used to compress valve springs and at 110 the same time allow withdrawal or replacement of the valve keys.

2. The combination with a flat base of a size to receive and support the detachable heads of valve-in-head motors, said base having an abutment extending longitudinally thereof near one edge against which the detachable head may be thrust, a rod supported above the base and abutment and parallel thereto, a lever loosely mounted at one end on the rod so as to be freely slidable and swingable thereon, said lever being forked intermediate its ends whereby it may be used to compress valve springs to permit withdrawal or replacement of the valve keys.
3. In a device for compressing valve springs, the combination with a support, a lever slidably and swingably mounted on the support, said lever being bent to form an offset portion intermediate of its ends, said offset having a part parallel to the principal length of the lever, and an arm integral with the lever and bent in a direction opposed to that in which the offset portion is bent so as to be substantially symmetrical with said portion, said arm however terminating at a point spaced from the lever whereby a gap or opening is left.
4. The combination with a base of a size to receive the detachable head of a valve-in-head motor, and a guide rod mounted on and

above the base, of a lever slidable and swingable on said rod and adapted to be moved along said rod to engage any one of the valves.

5. The combination with a base, of a lever, and means for pivotally connecting said lever to said base, said lever being bent to form an offset portion intermediate of its ends, and an arm integral with the lever and terminating at a point spaced from the lever, whereby a gap or opening is provided at an intermediate point of the lever.

6. The combination with a flat base of a size to receive and support the detachable heads of valve-in-head motors, said base having an abutment extending longitudinally thereof near one edge against which the detachable head may be thrust, a rod supported above the base and abutment and substantially parallel thereto, and a lever loosely mounted at one end on the rod so as to be freely slidable and swingable thereon, whereby it may be used to compress valve springs to permit withdrawal or replacement of the valve keys.

In testimony, that I claim the foregoing as my own I have hereto affixed my signature.

HENRY W. PAINE.
